(57) **CLAIM**

The ornamental design for a grinding machine, as shown and described.

DESCRIPTION

FIG. 1 is a front, left and top perspective view of a grinding machine, showing my new design;

FIG. 2 is a rear, right and bottom perspective view thereof;

FIG. 3 is another perspective view, showing the lid rotated in a state of use;

FIG. 4 is another perspective view, showing the lid in an open state of use;

FIG. 5 is a front view, showing the lid in a closed state;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is a perspective view showing the lid being opened and inverted on a plane;

FIG. 12 is an enlarged view of portion 12 of FIG. 1;

FIG. 13 is an enlarged view of portion 13 of FIG. 2; and,

FIG. 14 is an enlarged view of portion 14 of FIG. 2.

The broken lines shown in the drawings illustrate portions of the grinding machine that form no part of the claimed design. The dot-dash-broken lines depict the boundaries of the enlargements that form no part of the claimed design.

1 Claim, 14 Drawing Sheets
